UNITED STATES PATENT OFFICE.

JOHN W. NILSSON, OF BALFOUR, NORTH DAKOTA, ASSIGNOR OF ONE-HALF TO N. B. ANDERSON, OF BALFOUR, NORTH DAKOTA.

DETACHABLE BUTTON.

1,050,380.

Specification of Letters Patent. Patented Jan. 14, 1913.

Application filed August 4, 1910. Serial No. 575,458.

To all whom it may concern:

Be it known that I, JOHN W. NILSSON, a citizen of the United States, residing at Balfour, in the county of McHenry, State of North Dakota, have invented certain new and useful Improvements in Detachable Buttons; and I do hereby declare the following to be a full, clear, and exact description of the invention, such as will enable others skilled in the art to which it appertains to make and use the same.

This invention relates to improvements in detachable buttons, and has for one of its objects to improve the construction and increase the efficiency and utility of devices of this character.

Another object of the invention is to provide a simply constructed device which may be readily coupled to and uncoupled from the garment without disfiguring the garment and without destroying any of the parts of the improved button.

With these and other objects in view, the invention consists in certain novel features of construction as hereinafter shown and described and then specifically pointed out in the claim; and, in the drawings illustrative of the preferred embodiment of the invention, Figure 1 is a view of the improved button viewed from the outer side, Fig. 2 is a view of the improved button viewed from the inner side, Fig. 3 is a section on the line 3—3 of Fig. 1, Fig. 4 is a perspective view of the inner plate, detached, Fig. 5 is a perspective view of the locking member, detached.

The improved device comprises an outer shell or casing 10 and an inner shell 11, the two shell portions being united by crimping the edge of the outer shell over the edge of the inner shell, as shown at 12 in the ordinary manner. Located between the shell members 10—11 and preferably bearing against the outer face of the outer shell 10 is an inner plate 13, the plate being secured in any suitable manner to the shells, by being engaged between the crimping edges of the shells, as shown in Fig. 3.

The plate 13 is formed with spaced clefts extending inwardly from its edges whereby spaced tongues 14—15 are produced which are bent laterally at right angles to the plate and perforated, as shown at 17—18. The in-

ner shell 11 is provided with elongated aperture or slot 19 through which the catch device is inserted.

The three members 10—11—13 constitute the button proper, which is located externally of the garment, and the fastening device whereby the button is detachably coupled to the garment is preferably formed from a single piece of wire and is illustrated in Fig. 5. The fastening device is formed from a single piece of wire bent intermediate its ends into two loops 20—21 and with the remaining portion of the wire extended into spaced arms 22—23, the arms being flattened at the outer end and formed with inwardly directed barbs 24—25. The fastening member is formed from resilient wire with the barbs 24—25 normally spaced in relatively close relations.

To couple the button structure to a garment the pointed and barbed portions 24—25 are forced through the material of the garment from the inside, the material being represented conventionally at 26 and the barbed terminals forced through the slot 19 and over the outer faces of the tongues 14—15 until the barbs engage in the apertures 17—18, which operation will automatically couple the fastening device to the button and firmly lock the button to the garment. The loop 20—21 being extended in opposite directions from a support which bears against the inner faces of the garment material, and prevents the button being withdrawn. The fastening member shown in Fig. 5 will be as heavy as possible consistent with the size of the button proper, so that when coupled to the garment the button will resist any strains to which it will be subjected.

The button may be readily detached as required by inserting a suitable implement between the portions of the arms 22—23 which are located between the button and the garment material, until the barbs 24—25 are detached from the tongues 14—15.

The improved device is simple in construction, can be inexpensively manufactured and of any suitable material and of any desired ornamental design.

It will also plainly be seen that upon any outward pulling upon the button the rear wall 11 of the same will bear upon the di-

verging arms or tines 22 and 23 for positively holding the hooks 24 and 25 in engagement with the ears 14 and 15.

What is claimed is:—

The combination with a hollow button having an outwardly bowed rear wall and a flat front wall, of spaced perforated ears projecting inwardly of the button from the front wall thereof, the said rear wall being provided with a central elongated slot at right angles to said ears, a fastener formed from a single strand of relatively stiff wire and bent to provide a base and forwardly diverging tines, hook ends formed on the

said tines for engagement in the perforated ears, the said tines being inserted through the slot for engaging the hook ends in the perforated ears and on outward pulling upon the button the rear wall of the same will bear against the diverging tines for positively holding the hook ends in engagement with the ears.

In testimony whereof, I affix my signature, in presence of two witnesses.

JOHN W. NILSSON.
